[57] CLAIM

The ornamental design for a multiple magnification mirror, as shown and described.

DESCRIPTION

FIG. 1 is a front perspective view of a multiple magnification mirror according to the present invention.

FIG. 2 is a front elevation view thereof.

FIG. 3 is a rear elevation view thereof.

FIG. 4 is a right side elevation view thereof, the left side elevation being identical thereto.

FIG. 5 is an upper plan view thereof; and,

FIG. 6 is a lower plan view thereof.

The broken lines are for environmental purposes only and form no part of the claimed design.
